UNITED STATES PATENT OFFICE.

OTTO KUNTZEN, OF BERLIN, GERMANY.

FARE-INDICATOR.

SPECIFICATION forming part of Letters Patent No. 691,639, dated January 21, 1902.

Application filed May 4, 1901. Serial No. 58,779. (No model.)

To all whom it may concern:

Be it known that I, OTTO KUNTZEN, a subject of the German Emperor, residing in Berlin, Germany, have invented an Improvement 5 in Fare-Indicators, of which the following is a specification.

My invention relates more particularly to that class of fare-indicators which are adapted to be used on public conveyances, such as 10 cabs, and in which there is provided an indicator for the rates of fare to be paid, and there is also provided an indicator, usually in the form of a movable flag, to show whether the conveyance is engaged or disengaged, ("Free.")

15 My invention consists of improved means for actuating the indicating-flag.

In the accompanying drawings, Figure 1 is a sectional view through a part of the casing of the indicator and showing in elevation sufficient of the apparatus to illustrate my invention. Fig. 2 is a side view; and Fig. 3 is another sectional view through the case, showing the devices of Fig. 1 in side elevation.

The rate indications are set by means of a 25 crank - handle *d*, which actuates the same through some suitable intermittent self-locking feed motion. In the present instance the spindle of this crank *d* carries within the casing *x* a locking-disk *c*, with a single tooth to 30 engage with a notched disk *b*, shaped somewhat like a maltese cross and serving through suitable connections to actuate the rate-indicating devices. (Not necessary to be shown.) On the same spindle as this notched disk *b*

there is secured a disk *a*, provided with a cam-groove *e* in its side face. In the present instance I have shown this cam-disk *a* as outside the casing *x*; but its location may be arranged as convenient. Into this cam-groove *e* projects a pin *h* on a lever *f*, which is pivoted at *g* to the casing. The other end of the lever is connected by a connecting-rod *i* to an arm *k* on the axis *m* of the flag *l*, this axis being preferably mounted in a protecting-cover *n* on the casing *x*.

The curved or cam groove *e* is so formed that when any one of the price or rate indications is set by turning the crank *d* the lever *f* will be so turned in the direction of the arrow, Fig. 2, that the flag *l* will be turned 45 down from the upright position (shown in the drawings) to a horizontal position, where its designation "Free" will no longer be visible to the public.

I claim as my invention—

A fare-indicator provided with a movable flag, a cam-grooved disk for actuating the flag positively in both directions, and an intermittent feed mechanism for actuating the cam-grooved disk each time one of the price or rate 60 indications is set.

In testimony whereof I have signed my name to this specification in the presence of two subscribing witnesses.

OTTO KUNTZEN.
